Inventor:

Edward W. Bretell

United States Patent Office.

EDWARD W. BRETELL, OF NEWARK, NEW JERSEY.

Letters Patent No. 63,204, dated March 26, 1867.

IMPROVEMENT IN DOOR-LOCKS.

The Schedule referred to in these Letters Patent and making part of the same.

TO ALL WHOM IT MAY CONCERN:

Be it known that I, EDWARD W. BRETELL, of Newark, in the county of Essex, and State of New Jersey, have invented certain new and useful improvements in Locks for Doors, &c., and do hereby declare that the following is a full and exact description thereof, and therefore pray that Letters Patent may be granted to me. The accompanying drawings form a part of this specification.

Figure 1 is a front view of my improvement, showing the natural position of its several parts.
Figure 2 is a view of a vertical tumbler.
Figure 3 is a front and edge view of the casing.
Figure 4 is a front and edge view of the lever, dog, and key-socket.
Figure 5 is a view of the key.
Figure 6 is a front view, with the front plate removed, so as to show it in a locked position.
Figure 7 is a view unlocked.
Figure 8 is an edge view, showing the position of the tumblers in the recess of the key-socket with the key out.

Figure 9 is an edge view with the key in.
Similar letters of reference indicate like parts in all the figures.
My invention is intended to make a lock more secure against "burglars," and little objectionable on account of cost.

To enable others skilled in the art to make and use my invention, I will proceed to describe its construction and operation, by the aid of the drawings and of the letters of reference marked thereon.

Figure 1 is a case of tumblers which can be arranged in all classes of locks, the casing being either separate from or cast in the lock.

Figure 2, S, is a self-acting, vertical, sliding tumbler, with a slot, o, to admit the dog d on the lever B: By the use of the proper key the tumblers S are raised so as to bring the slots o opposite to the dog d on the lever B, when, by turning the key, the lever B may be thrown freely backwards or forwards, as shown in figs. 6 and 7.

Figure 3, A, is a case with two checks, e and e', which are placed in any lock, for the purpose of holding the tumblers in their proper places, as shown in fig. 8.

Figure 4, B, is a lever with a dog, d; attached to the key-socket m, for the purpose of throwing back the bolts or latches of locks. f is a square end of the key-socket m, which may be placed in the knob-hole of a lock, thus making it applicable to all latch-locks. R is a recess in the key-socket m, in which the tumblers S set when the key is out, partly closing the key-hole, as shown in fig. 8.

Figure 5, K, is a flat key, so notched on the edge as to raise the tumblers S, with their slots, o, opposite the dog d on the lever B, thus allowing the free action of lever B to throw a bolt or latch. x is a slot in the key-socket m to admit a key, as shown at fig. 4.

Having now fully described my improvement, what I claim as new, and desire to secure by Letters Patent, is as follows:

1. The encasing of a series of self-acting, vertical, sliding tumblers, with their operating dog, within an independent detachable case, substantially as herein shown and described.

2. The dog d attached to the lever B, so as to act independently of both the bolt and the lock-case, substantially as herein shown and described.

EDWARD W. BRETELL.
